UNITED STATES PATENT OFFICE.

EDWARD F. WINFIELD AND OTTO KERNER, OF LOS ANGELES, CALIFORNIA.

MULTIPLE-ARC LAMP.

Application filed August 18, 1919. Serial No. 318,117.

To all whom it may concern:

Be it known that we, EDWARD F. WINFIELD and OTTO KERNER, citizens of the United States, residing at Los Angeles, in ⁵ the county of Los Angeles, State of California, have jointly invented new and useful Improvements in Multiple-Arc Lamps, of which the following is a specification.

This invention relates to arc lamps; and, ¹⁰ without being limited thereto, relates more specifically to such arc lamps as are particularly adapted for motion picture and other photographic work.

In such lamps it is desirable to maintain ¹⁵ arcs as nearly uniform as possible and to have the least possible fluctuation upon the periodic striking of the arc. It is an object of this invention to accomplish these desirable qualities; and, furthermore, to accomplish them in a multiple arc mechanism. ²⁰ And, generally, it is an object of the invention to provide an efficient multiple arc lamp, simple and effective in structure and operation, in which there is uniformity of ²⁵ operation and a minimum of fluctuation of the several arcs. We illustrate a lamp having two arcs; but our structures and our modes of operation may be applied to a single arc or to more than two arcs. The ³⁰ present invention provides an arc lamp which is particularly adapted for motion picture photography. It provides an even steady light, which is necessary for successful taking of motion pictures. This makes ³⁵ the invention of great commercial value and superior to ordinary arc lamps for this particular class of work, as it minimizes the cost of retaking pictures. A great saving is effected by the invention in this class of ⁴⁰ work as it eliminates a waste of valuable film which is very large when an ordinary arc lamp is used.

The details of construction and operation of a preferred form of lamp embodying the ⁴⁵ invention will be understood for the following description, reference for this purpose being had to the accompanying drawing, in which:

Fig. 1 is a front elevation of the preferred ⁵⁰ form of mechanism; Fig. 2 is a section taken as indicated by line 2—2 on Fig. 1; Fig. 3 is a side elevation; Fig. 4 is a plan view; Fig. 5 is an enlarged detailed section taken

as indicated by line 5—5 on Fig. 3; Fig. 6 is ⁵⁵ an enlarged detailed section taken as indicated by line 6—6 on Fig. 1; and Fig. 7 is a plan section taken on line 7—7 of Fig. 3.

In a preferred form of the invention we preferably use two arcs. The lower carbons 10 of these arcs are supported and held ⁶⁰ in suitable supporting brackets 11 and clamps 12. The upper carbons 13 extend through clutch mechanisms 14. The clutch mechanism 14 for each of the upper carbons ⁶⁵ 13 embodies a vertically movable clutch plate 15 having an aperture 16 through which the carbon passes. At its forward end this clutch plate 15 is pressed downward by a spring 17 coiled around a guide rod or post 18, which passes through an ⁷⁰ aperture 19 in the forward part of the clutch plate. The post 18 extends between bracket 20, which is mounted on a frame 21, and a guide plate 22. The guide plate 22 is mounted on posts 23. A stop screw ⁷⁵ 24 extends downwardly from the guide plate 22 and is screw-threadedly engaged in said plate. The guide plate 22 is split where the stop screw 24 passes through it and a set screw 25 is provided to clamp the screw 24 in place. The stop screw 24 forms a stop for the clutch plate ⁸⁰ 15 and limits its upward movement. The carbon 13 moves and is guided vertically through aperture 26 in guide plate 22 and aperture 27 in bracket 20.

The arrangement and organization of the parts is such that when the rear of the clutch plate is moved upwardly to a somewhat angular position, the carbon is bound ⁹⁰ in the aperture 16; and when the carbon is so bound, then the carbon and the clutch plate will move upwardly together against the downward pressure of spring 17. Whenever the clutch plate moves down to the position shown in the drawings, that is, when the current is turned off, it seats flatly upon the bracket 20. Then the carbon ⁹⁵ 13 will be released and may fall immediately upon the lower carbon 10. It will be noted that the forward or outer part ¹⁰⁰ 15^a of the clutch plate is turned up diagonally, so that the downward pressure of spring 17 tends to prevent the forward part of the clutch plate from lifting too high; and ¹⁰⁵ keeps the plate tipped when the back edge

is raised. The action of the spring is to assist the clutch plate to tip before it begins its bodily upward movement and thereby clutch the carbon at the inception of its upward movement.

The rear end of each clutch plate 15 is connected to a lever arm 30 by links 31. The links are normally loose when the mechanism is at rest or when the clutch plates are seated and the carbons are being dropped. The arm 30 is pivotally mounted at 32 on a bracket 32^a and has extending through it a set screw 33 which engages an insulating sleeve 34 carried on a transverse rod 35. The insulating sleeve 34 is mounted on one end of a lever 36 which is pivotally mounted also at 32 on bracket 32^a, arm 30 being forked as shown in Fig. 4, to allow this construction. In the other end of arm 36 there is an insulating sleeve 37 in which is carried a rear cross rod 38. A motion steadyng device, preferably in the form of a small dash-pot mechanism 39, is connected at 40 to each lever 36. This mechanism comprises the simple arrangement of a small cylinder 41 having therein a piston 42 fitting the cylinder more or less tightly, the piston being mounted upon a rod 43 which is connected at 40 to the lever 36. The cylinder 41 has an upward extension 44 pivotally connected at 45 to the upper end of a suitable bracket 46^a; and extension 44 carries a valve 46 which may be arranged to check inward movement of air into the cylinder. The leakage of air around piston 42 allows slow downward movement of the piston in its cylinder; the upward movement is relatively free.

We have now described in detail the immediate operating mechanism for each carbon; and there will be as many of such mechanisms as there are carbons in the multiple lamp. In the present case there are only two, but it will be readily understood by those skilled in the art how the parts of the mechanism now about to be described may be adapted to different numbers of carbon operating mechanisms. And it may be well to point out here that it is not necessary to have an individual dash pot for each carbon mechanism.

The forward cross-rod 35 and rear cross-rod 38 connect the arc lamp mechanisms. Rod 35 extends through the sleeve 34 of each mechanism and cross-rod 38 extends through sleeve 37 of each mechanism. On the ends of cross-rod 35 are rigidly mounted arms 50. One end of each of the arms 50 is rigidly connected to cross-rod 38 while on the other ends of the arms are adjustable counterbalance weights 51. The counterbalance weights being adjustable, may be set or regulated to suit the voltage and friction of the mechanism. Mounted on the back side at the lower end of frame 21, is a solenoid 52 pro-

vided with a core 53 adapted to be drawn downwardly into the solenoid. Core 53 is connected, through the medium of a spring 54 and arm 55 to cross-rod 38. In order to prevent the core 53 from being accidentally removed from the solenoid a heavy wire or small rod 56 (preferably non-magnetic) extends from the lower end of the core through the solenoid. The lower end of wire 56 is bent as shown in Fig. 3 so as to prevent the core from accidentally passing out of the solenoid.

The counter weights 51 tend to keep the entire mechanism in the position as shown in the drawings. If so desired springs may be substituted for weights 51. The loose link connections at 31 allow the clutch plates always to rest flatly on brackets 20 so that when the pull of solenoid 52 is released, the spring 54 and dash pots 39 damp off vibrations in the carbon operation mechanisms which would otherwise be excessively caused by vibrations of core 53. It is to be noted that the arms 50 and the cross-rods 35 and 38 form a rigid frame and that arms 36 move rigidly with that frame. All these parts, and also arms 30, oscillate about the axis 32 as a center. By adjustment of screws 33 the looseness of links 31 may be adjusted in equality, so that, when the solenoid acts to tilt the oscillating members and lift the loose links, the several carbons will begin to rise at the same time and will be lifted equal distances. The several arcs are connected in series and the solenoid 52 is also connected in the same series circuit. The two supply wires 60 and 61 lead to binding posts 62 and 63, respectively. A wire 64 leads from a binding post 62 to the lower carbon 10 of one of the arcs. From the upper carbon of this arc a wire 65 leads to the lower carbon of the other arc. From the upper carbon of the second arc a wire 66 leads to solenoid 52 and a wire 67 leads out of the solenoid to binding post 63 and thus to the other supply wire 61. In each case the wires 65 and 66 are divided into two parts which are connected together by connecting with binding clamps 70. The upper parts of these wires, being the parts that connect directly to the upper movable carbons 13, are preferably flexible so as to allow the proper movements of the carbons.

When the mechanism is at rest and there is no current flowing, the parts are in the position shown in the drawings. As soon as current is supplied, the carbons being in contact, the solenoid is energized and draws core 53 downwardly. Spring 54 and the inertia of the parts (and the weights 51 play a part during the first movement of taking up the looseness in the links 31) serve to take up any sudden shock, and dash-pots 39 also serve to retard the movement of levers 130

36. The clutch mechanism is gradually moved upwardly, the rear ends of clutch plates 15 first moving upwardly, tipping the clutch plates in the manner hereinbefore described and causing the clutch plates to immediately bind the carbons. Further upward movement of the clutch plates then lifts the carbons and separates the upper carbons from the lower carbons, forming arcs which are gradually lengthened until the clutch plates strike stop screws 24. The stop screws 24 are set so that the arcs are not initially pulled out to their maximum length. The burning away of the carbons causes the arcs to lengthen, and to increase the resistance in the circuit and to thereby decrease the pulling power of the solenoid. As the arcs gradually lengthen, the solenoid core 53 moves upwardly, lowering the clutch plates 15 as the carbons burn away. A fair balance is struck between the forces tending to lower the carbons and the solenoid force tending to raise them, so that the arcs are kept at a substantially constant length. However, as the core 53 moves upwardly it moves to a position where, for a given amount of current in the solenoid, it is attracted downwardly with a greater force; and the result of this is that as time goes on, the lengths of the arcs are somewhat increased. This action is caused by the relation of the core to the solenoid, its lower end moving from a position below the center of the solenoid to a position when it is entirely above said center or in about the same relation to the solenoid as shown in the drawings; and the solenoid not having a magnetic end plug. The clutch plates are gradually lowered until they strike the brackets 20, releasing the carbons and allowing them to drop slightly and enough to decrease the resistance in the circuit when the solenoid immediately lifts the clutch plates and carbons. The arcs are thus kept substantially uniform without the necessity of frequent restriking. There is some fluctuation in the arc resistance and the core 53 vibrates to some extent at all times. The spring 54 and the dash pot 39 take up most of this vibration; in fact, due to the action of the spring and the link connection and the inertia of the various parts of the mechanism particularly the weights 51, practically none of this vibration reaches the carbons themselves. If for any reason one arc is broken, the current then ceases to flow and the parts all instantly drop to the position shown in the drawings, and both upper carbons drop on the lower carbons. The current is again established and the mechanism immediately clutches the carbons and raises them to form new arcs. Such restriking of the arcs evens up the lengths thereof in event that one of them has become too long due to uneven dropping of carbons through the clutch plates in the normal operation, which uneven feeding causes breaking of the longer arc and therefore restriking of both. The operation of dropping the carbons and breaking them up and forming new arcs is almost instantaneous.

The dash pots 39 retard and steady the movements which raise the upper carbons. It will be noted that although these dash pots are independent and the clutch mechanisms, etc., are also independent of each other, the mechanical construction and actuation is such that both of the carbons are dropped simultaneously. This simultaneous dropping of the carbons causes the equalization of any difference in lengths of the arcs if the carbons are dropped.

The dash pots 39 also have, in combination with the spring 54, a direct effect in the operation which causes the final breaking of the arc and resetting of the carbons. It is to be noted that the dash pots resist only upward movement of the carbon. Thus, although the carbons may move downwardly and shorten the arcs, in vibrations or fluctuations caused by vibratory movement of core 53, yet the upward movement of the carbon is relatively slow; the tendency being to expand spring 54 rather than move the carbons quickly upwardly. The result of course is that the major portion of the vibrations is taken up in the spring 54, without any excessive vibratory movement of the carbons, either up or down. The arc is thus steadied and held constant; and at the same time the gradual downward movement of the clutches and of the carbons, as the carbons burn away, is not opposed.

The above description has been that of the lamp mechanism separate from any covering or casing. It will be readily understood however, that the mechanism can be readily installed or mounted in various forms of casings and that the invention is entirely independent of any casing or housing in which the lamp may be installed.

We have now explained, in its preferred form, an arc lamp embodying our invention; and certain features of our invention will be understood to be included in the mechanical arrangement and organization of parts to efficiently accomplish the ends herein set forth. But the primary feature of the invention is the provision of an efficient form of single or multiple arc lamp, and particularly a multiple arc lamp, with mechanism for its efficient operation, gradual feeding and for giving a steady unvarying light.

Regarding our invention as being broad in its scope we do not limit ourselves to the specific details herein set forth, but reserve whatever changes or modifications that may suggest themselves to those skilled in the art or fall within the scope of the following claim.

Having described a preferred form of our invention, we claim:

In an arc lamp mechanism, a frame with means for carrying a stationary carbon and a guide for a movable carbon, a clutch plate adapted when lifted to engage and lift the movable carbon and when lowered to release the movable carbon, an oscillating frame mounted on the first mentioned frame, an adjustable weight carried by the oscillating frame at one side of its pivot, a solenoid, spring connective means between the solenoid and the frame, a motion retarding means connected to the frame to retard upward movement of the weighted side of the frame and to allow free downward movement thereof, an arm connected to and oscillating with the oscillating frame and having an end projecting past the oscillating

center on the weighted side of the frame, 20 a free arm pivoted on the oscillation center of the frame, adjustable means on said free arm resting on the end of the oscillating arm so that the position of the free arm may be adjusted with reference to the oscillating arm and frame and so that upward movement of the weighted side of the frame raises the free arm and downward movement of that side of the frame leaves said arm free to fall, and a loose link connection between the free arm and the carbon clutch. 25 30

In witness that we claim the foregoing we have hereunto subscribed our names this 11 day of Aug. 1919.

EDWARD F. WINFIELD.
OTTO KERNER.
